UNITED STATES PATENT OFFICE.

MELVIN ROBERT SMITH, OF DANBURY, CONNECTICUT, ASSIGNOR TO D-FLECTO LIGHT COMPANY, OF DANBURY, CONNECTICUT.

DESIGN FOR A DEFLECTOR FOR HEADLIGHTS.

Application filed July 16, 1925. Serial No. 14,111. Term of patent 7 years.

To all whom it may concern:

Be it known that I, MELVIN ROBERT SMITH, a citizen of the United States, residing at Danbury, in the county of Fairfield and State of Connecticut, have invented a new, original, and ornamental Design for Deflectors for Headlights, of which the following is a specification, reference being had to the accompanying drawing, forming part thereof.

Fig. 1 is a plan view of a deflector for headlights, showing my new design.

Fig. 2 is a side elevational view thereof as seen from the left in Fig. 1; and

Fig. 3 is an edge view as seen from the top in Fig. 1.

I claim:

The ornamental design for a deflector for headlights, as shown.

MELVIN ROBERT SMITH.
